UNITED STATES PATENT OFFICE

EARL B. LEAR, OF PHILLIPSBURG, NEW JERSEY, ASSIGNOR TO INGERSOLL-RAND COMPANY, OF JERSEY CITY, NEW JERSEY, A CORPORATION OF NEW JERSEY

BLOWING DEVICE FOR ROCK DRILLS

Application filed July 16, 1931. Serial No. 551,149.

This invention relates to percussive tools, but more particularly to a blowing device for fluid actuated percussive tools of the hammer type.

One object of the invention is to selectively admit pressure fluid under full line pressure to the drill steel for cleansing the drill hole and another object is to maintain the distributing valve and the hammer piston of the drill stationary during the blowing operation.

Other objects will be in part obvious and in part pointed out hereinafter.

In the accompanying drawing in which similar reference characters refer to similar parts,

Figure 1 is a sectional elevation of a percussive tool having the invention applied thereto and showing the position of the parts during the blowing operation, and

Figure 2 is a fragmentary view showing the position of the valve holding device during the normal operation of the drill.

Referring more particularly to the drawing, A designates generally a percussive tool of the hammer type comprising a cylinder B having a piston chamber C therein to accommodate a reciprocatory hammer piston D.

The piston D may be of a well known type having a head E slidable in the piston chamber and controlling a free exhaust port F in the cylinder B. On the front end of the piston D is an integral stem or extension G having a series of flutes H to interlock with ribs J carried by a chuck K which is encased by a front head L.

The chuck K may rotate freely within the front head L and is adapted to receive the shank end of a working implement O, as for instance a drill steel, which may be suitably interlocked with the chuck in a well known manner to rotate therewith. A front cylinder washer P interposed between the cylinder B and the front head L may extend part way into each and has a bore Q to serve as a guide for the extension G of the piston.

Seated on the rear end of the cylinder B is an extension R having an end wall S at its forward or inner end to serve as a closure for

the rearward end of the piston chamber C. The rear end of the wall S acts as a seat for a distributing valve T of the oscillatory plate type arranged in a valve chamber U for which a plate V disposed in the extension R serves as a rearward closure. The valve T is of a well known type adapted to oscillate or rock from one limiting position to another to control the distribution of pressure fluid from the valve chamber U to the ends of the piston chamber C. The admission of such pressure fluid into the rear end of the piston chamber for actuating the piston D is conveyed thereto by a rear inlet passage W in the wall S, and a front inlet passage X formed in the wall S and the cylinder B serves to convey pressure fluid from the valve chamber U to the front end of the piston chamber C.

The tool may be provided with rotation mechanism of a well known type designated generally by Y and comprising, as illustrated, a rifle bar Z which may extend into and interlockingly engage the piston D in the usual manner. A ratchet ring b seated on the rear end of the plate V encircles a head c carried by the rifle bar Z to act as an abutment for spring pressed pawls d carried by the head. The ratchet ring b moreover, acts as a seat for a back head e which serves as a closure for the rear end of the tool to which it may be secured, as may also be the extension R, by means of the usual spring pressed side bolts (not shown).

The back head e is shown provided with a throttle valve f to control communication between a source of pressure fluid supply and a passage g in the back head e and which passage opens into a supply reservoir h also in the back head. Communication between the supply reservoir h and the valve chamber U is afforded by supply passages j in the ratchet ring b and the plate V.

In accordance with the practice of the invention means are provided for assuring an uninterrupted supply of pressure fluid to the drill hole whenever the detritus tends to accumulate therein and which, if not expelled from the drill hole, will form a collar adjacent the cutting bit and seriously impede the

action of the rotation mechanism. To that end the extension R is provided with a bore k to slidably receive a plunger o having a button p on its outer end against which pressure may be applied for actuating said plunger. The button p also serves as a seat for one end of a spring q which encircles the plunger o and seats with its opposite end against the extension R.

10 The plunger o may be retained in the bore k in any suitable manner, as for instance, by means of a pin r disposed in the extension R and extending through an elongated slot s in the surface of the plunger o. The inner 15 end t of the plunger may extend into the valve chamber U and on the lower side of the plunger o, adjacent the end t is an inclined surface u which, when the plunger o is actuated in the direction of the valve chamber, will engage the rear surface of the valve and press the end of the valve tightly upon its seat to close the rear inlet passage W.

In order to assure a suitable pressure in the rear end of the piston chamber C so that the 20 pressure acting against the front end of the head E of the piston will be unable to actuate the piston into a position to place the front end of the piston chamber C in communication with the atmosphere through the free 25 exhaust port F, the plunger o is provided with a passage v which, when the plunger is depressed to lock the valve in position, will be in communication with the valve chamber U and also with a passage w in the extension R, 30 and which latter passage opens into the rear end of the piston chamber C.

The operation of the device is as follows: With the throttle valve f in the open position 35 pressure fluid will flow into the valve chamber U where it will be normally distributed by the valve T and flow to the rear and front ends of the piston chamber C through the inlet passages W and X respectively. The piston D will then reciprocate to deliver its 40 blows against the working implement O and during its reciprocations will place the ends of the piston chamber alternately in communication with the atmosphere through the exhaust port F for exhausting the fluid utilized 45 for actuating the piston.

During this operation of the tool a portion 50 of pressure fluid will flow through the flutes H, thence through the drill steel O into the drill hole during each admission of pressure 55 fluid to the front end of the piston chamber C to remove the cuttings from the drill hole.

As the depth of the drill hole increases, it 60 becomes increasingly difficult to completely remove all the cuttings so that, in consequence 65 of the cuttings will accumulate therein and bring about the unfavorable condition hereinbefore referred to.

Whenever it becomes apparent that the alternate puffs of pressure fluid issuing from 70 the front end of the piston chamber C are in-

adequate to maintain the drill hole free from cuttings the plunger o may be depressed to the position illustrated in Figure 1. In this position the inclined surface u will engage the rear end of the valve and hold the valve 75 tightly seated over the rear inlet passage W.

The opposite end of the valve will then be fully raised and pressure fluid will flow from the valve chamber U through the front inlet 80 passage X and through the front end of the piston chamber C, thence through the flutes H and through the drill steel O into the drill hole to blow the cuttings therefrom. In the locking position of the plunger o the passage v will be in communication with the valve 85 chamber U and also with the passage w. Pressure fluid will therefore be admitted in restricted quantity, as compared with that flowing through the passage X, into the rear end of the piston chamber C to maintain a suitable pressure therein to balance that acting against the forward pressure area, or areas of the piston D.

In tools, wherein the piston is provided throughout its length with a bore such as is required to accommodate the rifle bar and, as illustrated, also a water tube z which extends into the working implement, a pressure suitably balancing that in the front end may be maintained in the rear end of the piston chamber 95 since, whenever the pressure rearwardly of the piston predominates slightly over that in the front end of the piston chamber, the pressure fluid will leak through the piston to the drill steel. The pressure in the rear end 100 of the piston chamber will thus be lowered to the same value as that existing in the front end.

The blowing device is, however, applicable for use in connection with tools employing solid pistons. When so used the excess of pressure which may accumulate in the rear end of the piston chamber will merely depress the piston D sufficiently to slightly open the exhaust port F, whereupon such excess pressure fluid will escape and the piston D may then immediately return to close the exhaust port F. In tools, however, such as that illustrated wherein pressure fluid may pass through the piston it has been found that 110 the pressure fluid acting against the opposing end areas of the piston will be balanced and that the piston will therefore remain immovable during the blowing operation.

After the drill hole has been properly 115 cleansed the plunger o may be released and the springs q may move it out of the path of the valve T and will hold it there during the subsequent normal operation of the drill.

I claim:

1. A fluid actuated rock drill comprising a casing having a piston chamber and an exhaust port, a hammer piston in the piston chamber controlling the exhaust port and having a blower passage, an automatic valve 130

for distributing pressure fluid to the piston chamber, and means for holding the valve in position to supply pressure fluid to only one end of the piston chamber and to the 5 blower passage and having a passage admitting pressure fluid to the other end of the piston chamber to prevent the piston from communicating the first said end of the piston chamber with the exhaust port.

10 2. A fluid actuated rock drill comprising a casing having a piston chamber and an exhaust port, a hammer piston in the piston chamber controlling the exhaust port and having a blower passage, an automatic valve 15 for distributing pressure fluid to the piston chamber, and means for holding the valve in position to supply an unrestricted volume of pressure fluid to only one end of the piston chamber and the blower passage and said 20 means admitting a restricted supply of pressure fluid into the other end of the piston chamber to maintain the piston in position to cover the exhaust port.

25 3. A fluid actuated rock drill comprising a casing having a piston chamber and an exhaust port, a hammer piston in the piston chamber controlling the exhaust port and having a blower passage, a valve chamber having an automatic valve therein to distribute 30 pressure fluid to the piston chamber, a plunger for holding the valve in position for supplying pressure fluid to one end of the piston chamber and to the blower passage, and restricted passages in the plunger and the 35 casing to convey pressure fluid from the valve chamber into the other end of the piston chamber to prevent the piston from communicating the first said end of the piston chamber with the exhaust port.

40 4. A fluid actuated rock drill comprising a casing having a piston chamber and an exhaust port, a hammer piston in the piston chamber controlling the exhaust port and having a blower passage, a valve chamber 45 having an automatic valve therein to distribute pressure fluid to the piston chamber, a plunger for holding the valve in position for supplying pressure fluid to the front end of the piston chamber and to the blower passage, and passages in the plunger and the 50 casing to bleed pressure fluid from the valve chamber into the rear end of the piston chamber to resist the force of the pressure fluid acting against the front end of the piston 55 and thus maintain the piston in an intermediate position in the piston chamber to cover the exhaust port.

55 5. A fluid actuated rock drill comprising a casing having a piston chamber and an exhaust port, a hammer piston in the piston chamber controlling the exhaust port and having a blower passage, a valve chamber having an oscillatory plate valve therein to distribute pressure fluid to the piston chamber, a spring pressed plunger in the casing 65

to act upon the valve for cutting off communication between the rear end of the piston chamber and the valve chamber and to admit pressure fluid from the valve chamber into the front end of the piston chamber and to 70 the blower passage, a passage in the casing opening into the rear end of the piston chamber, and a passage in the plunger adapted to register with the passage in the casing for admitting pressure fluid into the rear end of 75 the piston chamber during the blowing operation to maintain the piston in an intermediate position in the piston chamber for closing the exhaust port.

In testimony whereof I have signed this 80 specification.
